CLAIM

We claim the ornamental design for a bottle, as shown.

DESCRIPTION

FIG. 1 is a top front left side perspective view of a bottle showing our new design;

FIG. 2 is a top plan view thereof;

FIG. 3 is a right side elevational view thereof; and,

FIG. 4 is a front elevational view thereof.

The broken lines shown in the drawings are for illustrative purposes only and form no part of the claimed design.
